ATTORNEY

UNITED STATES PATENT OFFICE.

HENDERSON M. POWERS, OF LANCASTER, PENNSYLVANIA.

APPARATUS FOR DRAWING LIQUIDS.

SPECIFICATION forming part of Letters Patent No. 329,945, dated November 10, 1885.

Application filed September 15, 1885. Serial No. 177,156. (No model.)

To all whom it may concern:

Be it known that I, HENDERSON M. POWERS, a citizen of the United States, residing at Lancaster, in the county of Lancaster, and 5 State of Pennsylvania, have invented certain new and useful Improvements in Apparatus for Drawing Liquids; and I do hereby declare the following to be a full, clear, and exact description of the invention, such as will enable 10 others skilled in the art to which it appertains to make and use the same.

This invention has for its object to allow 15 grocers or other store-keepers to conveniently withdraw liquids from barrels or other receptacles located at more or less distant points without being obliged to go to said receptacles; and, further, to provide for drawing two or 20 more different liquids into the same casing, insuring the separation of the overflow of said liquids and the return of each liquid thus overflowing to its own receptacle, and securing the pumps in position and protecting them from injury.

The said invention consists, partly, in the 25 combination of a casing divided into independent overflow compartments with outlet-pipes leading therefrom, valves for closing said outlet-pipes, and mechanism for operating said valves simultaneously, as hereinafter set forth.

The said invention further consists in the 30 combination, with each pump, of its supply-tube and an outlet-tube for overflow, the latter tube discharging into the former.

It also consists in the combination, with the 35 pump-supply tube and outlet-tube, of a valve and pitman for opening and closing said outlet.

It consists, finally, in certain special features 40 of construction and combination, hereinafter particularly set forth.

In the accompanying drawings, Figure 1 represents a plan view of the devices embodying my invention. Fig. 2 represents a central vertical longitudinal section of the same, 45 and Fig. 3 represents a vertical transverse section of the same through the valve-operating devices. Fig. 4 represents a detail vertical section of one of the pumps. Fig. 5 represents a horizontal section through the removable lower valve and casing, and Fig. 6 represents a detail perspective view, taken from

below of the clamping blocks, bolts, and screw for holding the pumps in place.

In said drawings, A designates a casing or box, the top of which preferably slopes from 55 the rear to the front after the manner of an ordinary coal-bin. This casing rests upon the floor of a room, and is provided with a hinged cover, A', opening sidewise. The lower part of it is divided by a longitudinal 60 partition, a, into two or more parts or compartments, A² A³, in each one of which is located a pump, B B', provided with a suction-piston, b, having a ball-valve, b'. In the lower end of the pump-casing is a removable supplemental valve, C, and thence a tube, D D', extends to a barrel in the cellar or any other 65 more or less distant receptacle for liquid. Compartment A² is provided with an outlet-pipe, E, which empties into the supply-tube D of 70 pump B in said compartment, and compartment A³ is likewise provided with an outlet-pipe, E', which extends similarly to the tube D' of pump B'. These outlet-pipes are opened and closed by outlet-valves F F', arranged, 75 respectively, in said compartments and suspended therein by pitmen G G'. The upper ends of these pitmen are hung on studs g g', eccentrically attached, respectively, to disks H H', carried by a horizontal transverse shaft, 80 I. This shaft is journaled in the ends of a bearing-drum, J, which is slotted, to allow the protrusion and operation of an arm, K, whereby said shaft is rocked, to raise or lower 85 said valves. This bearing-drum is formed with or attached rigidly to an upright longitudinal bracket-plate, L, which is bifurcated to embrace partition a, and bolted detachably thereto. Perforated false bottoms M are provided for said compartments, which allow 90 the oil or other liquid that drips from the pumps or overflows from the vessels filled thereby to pass down to the true bottom, but will prevent the passage of rubbish. These false bottoms are cut away around the pumps 95 and above the valves, as shown. The pumps are held in place by two clamp-blocks, N N', the former being bolted to the under side of the floor below the casing A, and the latter secured to said block N by a clamping-screw, 100 O, which works laterally and allows block N' to be withdrawn or advanced, as required.

When said block N' is forced tightly against the relatively stationary block N , the inner faces of said blocks, being recessed to embrace the casings of said pumps, will fit tightly against all points of their circumference, and hold them as in a vise. The removable lower valves, C , of said pumps are mounted in slides P , which are laterally movable in guideways p of said pump-casings, and provided with eyes p' , whereby they may be conveniently drawn out at will, exterior independent hooks catching into said eyes for that purpose. The removal in this manner of said slides and valves allows the latter to be repaired with great facility.

15 The construction of pumps, valves, and tubes shown for drawing from two barrels or reservoirs is the same when a greater number are employed, except only the increase or multiplication of corresponding parts. The outlets may of course be arranged at the end of the casing, with the outlet-valves external thereto; but the arrangement shown has the advantage of affording better protection to all the parts.

20 25 The operation is as follows: The grocer or other person desiring to use this apparatus attaches the tube D to one barrel of oil or other liquid, the tube D' to a barrel of another kind of liquid, and so on with all the tubes in use. The outlet-valves are normally closed, to prevent any dust or foreign matters from passing down through the outlet-pipes to the said barrels. When a customer calls for any particular kind of oil or other liquid, the pump appropriated thereto is worked to draw a sufficient quantity thereof. It is of course practically impossible to draw the exact amount required and no more. The overflow and also any dripping falls into the bottom of the compartment which contains said pump. It is prevented from mixing with that in any adjoining compartment by the interposed partition. Whenever it is thought best or proper, the shaft I is rocked so as to raise the outlet-valves and allow the liquid from each compartment to flow back to its proper reservoir, with no risk of mixing or going wrong. The shaft I is then turned back again, and the valves $F F'$ restored thereby to their former position, closing the outlets. By the use of these devices I am enabled without any risk of mixture, wastage, or contamination to draw any one or more of any convenient number of different liquids within the same casing without going near the barrels or other receptacles containing them, or leaving the store or the presence of the customer for

a moment. The practical advantages of this are obvious. They are further increased by the fact that two or more pumps may be simultaneously operated without interfering in the least with one another. Thus two clerks may wait on two customers at once, supplying them from the same casing. When they are not actually in use, the closing of cover A' will effectually protect the pumps and valves from the intrusion of foreign matter.

Having thus fully described my invention, what I claim as new, and desire to secure by Letters Patent, is—

1. The casing divided into independent overflow-compartments, in combination with outlet pipes leading therefrom, valves for closing said outlet-pipes, and mechanism for operating said valves simultaneously, for the purpose set forth.

2. The combination of a pump and its supply-tube with an outlet-tube which discharges into said supply-tube, and a valve for opening and closing the latter, substantially as set forth.

3. The combination of a pump and supply and outlet tubes or pipes with an outlet-valve, and a pitman for raising and lowering the same to open and close said outlet, substantially as set forth.

4. The combination of the outlet-valves and the shaft and intervening devices for operating them all simultaneously with the pumps, and the casing which receives and retains the several kinds of liquid in its compartments, substantially as set forth.

5. The removable lower valve, C , and the slide in which it is mounted, in combination with the pump-casing provided with lateral guideways which allow the withdrawal of said slide, substantially as set forth.

6. A casing divided into two or more compartments, in combination with pumps arranged one in each compartment, outlets and outlet-valves governing the discharge of overflow and waste liquid from each compartment, and tubes communicating respectively, with the several pumps to supply the same with liquid, each tube having connected to it the outlet-tube which returns the waste liquid of its pump, substantially as set forth.

In testimony whereof I affix my signature in presence of two witnesses.

HENDERSON M. POWERS.
